UNITED STATES PATENT OFFICE.

JULIAN P. LYON, OF DETROIT, MICHIGAN.

JAR-CLOSURE.

980,544.

Specification of Letters Patent.

Patented Jan. 3, 1911.

Application filed January 10, 1910. Serial No. 537,106.

To all whom it may concern:

Be it known that I, JULIAN P. LYON, a citizen of the United States, residing at Detroit, county of Wayne, State of Michigan, have invented a certain new and useful Improvement in Jar-Closures, and declare the following to be a full, clear, and exact description of the same, such as will enable others skilled in the art to which it pertains to make and use the same, reference being had to the accompanying drawings, which form a part of this specification.

This invention relates to jar closures.

It has for its object an improved jar closing cap and means for securing the same in place.

In the drawings:—Figure 1, is a side elevation of the jar and cap. Fig. 2, is a reverse plan view of the cap. Fig. 3, is a plan view of the jar mouth. Fig. 4, is a cross section of the jar at the line 4—4 of Fig. 3. Fig. 5, is a cross section at the line 5—5 of Fig. 3.

On the neck of the jar and external thereto slightly below the upper surface are cast a number of lugs 1, 1, 2, 2. Between the lugs are passages 3. The lugs 1 have their upper surface substantially parallel with the upper surface of the jar mouth and their under surfaces 5 also substantially parallel with the upper surface of the jar mouth. The locking lugs 2 which alternate with the lugs 1 have their upper surface substantially parallel with the jar mouth and their under surfaces 4 inclined thereto, taking the form on this surface of a small sized arc of a screw of quite short pitch.

The cover or cap 6 is made with indented portions 7 whose upper surface inside the cover is adapted to engage with the locking lug 2, and with the main body of that portion of the cover which is forced in by the indentation engaging beneath the lug and with a bearing surface 8 adapted to engage closely against the mutilated screw surface 4 and force the cap closely down with the tabular part of the cap bearing against the upper edge of the jar mouth with an interposed gasket or disk. The lugs 1 are made with an outer contour to engage closely with-

in the rim of the cap 6. Preferably, the extreme outer surface of the lug is extended slightly at its middle part beyond the line of a true circle having the center 10 more distant from the center than the length of a radius which will cut the point 5^a at the end of the lug, the object of this expansion being to prevent the web of the flange of the cap 6 from straightening or tending toward a straight line when it is forced to position with the inturned surface above the indentation 7 engaging under the locking lug 2, and in order that the lugs 5 may have an extent as large as possible, the passage 3 between the lugs 1 and 2 should be only sufficient to allow the indented part of the cap to pass freely between. The number of indentations and corresponding lugs is not material, provided there be at least four in all, in order that any tendency of the metal cap to become more or less oblong under the strain on at least two points, diametrically located, may be counteracted by the presence at each side of other lugs.

What I claim is:—

1. A jar closure, having in combination a jar provided with separate lugs surrounding the mouth thereof, having alternate locking lugs provided on their under surface each with an inclined face, a cap having a hanging flange and indentations therein corresponding to said lugs, the upper limit of the indentations being adapted to engage under the said lugs, and with the lugs alternating the locking lugs each with its middle part extended beyond the line of a true circle whereby each is adapted to bear against the hanging flange intermediate the indentations, substantially as described.

2. A jar closure, having in combination a jar provided with separated lugs surrounding the mouth thereof, alternate ones of said separated lugs being provided on their under surface each with an inclined face whereby a cap may be locked in its position over the top of the jar, a cap having a hanging flange and with indented portions therein, with the surface inclined on the upper face of each of said indented portions and with the lugs alternating the locking lugs on said jar

mouth extended at their middle point beyond the curvature of a true circle whereby the said lugs intermediate the locking lugs are adapted to engage against the hanging flange intermediate the indentations and force the said indentations securely under the locking lug, substantially as described.

In testimony whereof, I sign this specification in the presence of two witnesses.

JULIAN P. LYON.
